ELECTRIC CONVERTER FOR LUMINOUS
TUBES

William Foerste, Pelham Manor, N. Y., assignor
to Adolph Josepowitz, New York, N. Y., and to
said William Foerste

Application January 23, 1930, Serial No. 422,898

2 Claims. (Cl. 250—36)

The present application is a continuation in part of my application Serial No. 394,125, filed Sept. 20, 1929.

This invention relates to converting systems and apparatus for the conversion of a relatively low voltage direct current into a high voltage oscillatory current for use in operating luminous tubes or for any other purpose in which a high voltage current is to be used.

10 The broad object of the present invention is to provide a system of connections and apparatus including power oscillator tubes adapted to receive a direct current at a voltage, let us say 125 volts or even more, and convert it into a high voltage current capable of operating apparatus or devices such as luminous signs for instance.

20 A further object is to provide an improved converter for direct currents which dispenses with the use of a motor generator for producing the high voltage, high frequency current necessary for operation of luminous signs and other devices in which high frequency current is used.

25 Other objects and advantages of the invention will be hereinafter specifically pointed out, or will become apparent, as the specification proceeds.

30 With the above indicated objects in view, the invention resides in certain novel constructions and combinations and arrangements of parts, clearly described in the following specification and fully illustrated in the accompanying drawing, which latter shows embodiments of the invention as at present preferred.

35 In said drawing:

The single sheet of drawings represents a diagrammatic arrangement of apparatus for accomplishing the desired objects, the numerals 1 and 2 representing a number of power oscillator tubes which in the present case are adapted to act as oscillation generators for the production of an alternating current for operating a luminous sign 3. The circuit including the pair of wires 4 may be connected by means of a suitable attachment plug 5 to a source of direct current of say 125 volts.

40 The filaments 6 of the tubes 1 are connected in shunt relation to by-pass resistances 7 which are connected in series with fixed resistances 8, a variable resistance 9 and the filament 6 of the oscillator tube 2. A condenser 10 of suitable capacity is connected in shunt with one of the fixed resistances 8 and the variable resistance 9. The entire series circuit comprising the resistances 7, 8 and 9 and the filament 6 of tube 2

are connected directly to the pair of wires 4 comprising the power leads.

The variable resistance 9 is provided to permit adjustment of the filament current while the resistances 7 are provided to by-pass the plate current of the tubes 1 and 2. No by-pass resistance is required for the tube 2 since the plate current of none of the tubes can pass through the tube 2. The resistances 8 are provided to reduce the supply voltage to a safe value for heating the filaments of the vacuum tubes.

50 There is provided a transformer comprising a core 11 of magnetic material upon which is provided a plurality of coils 12a, 12b, 12c and 12d respectively, for a purpose now to be described. The grids of all of the oscillator tubes 1 and 2 are connected in parallel and the common wire is connected to one end of the coil 12a, the other end of the coil 12a being connected to the negative side of the direct current supply line.

55 One end of the coil 12b is connected to the wire leading to the common connection of the grids while the other end of the coil 12b is connected to one of the terminals of the luminous tube. The other terminal of the 60 luminous tube is connected to one end of the coil 12c, the other end of the coil 12c being connected to a wire which is in turn connected to all of the plates of the tubes. One end of the coil 12d is likewise connected to the common wire to the plates and the other end is connected to the positive side of the direct current line.

65 Preferably the coil 12a may consist of eight hundred turns while the coils 12b and 12c have five thousand turns each. The coil 12d is preferably of one thousand turns. Coils 12a and 12b, being connected in series, may be 70 considered as one coil, while coils 12c and 12d, being connected in series, may also be considered as one coil. All of the coils are wound so that

75 if they were connected in series the magnetic forces produced would be added to each other, in other words the coils are additively wound. For the purpose of protecting the transformer from possible high voltage surges there is provided a spark gap 13 which is so adjusted that

80 when the voltage exceeds a safe value a spark discharge will occur relieving the transformer windings of the strain imposed by excessive voltage. Preferably the spark gap is mounted as 85 near as possible to the transformer as will be readily understood by persons skilled in the art.

85 A condenser 14 of suitable capacity to by-pass high voltage alternating currents produced by the oscillators is connected across the lead wires 90

95 100 105 110

4. The condenser 14 prevents the alternating currents produced by the tubes from causing interference with the operation of radio apparatus in the vicinity of the converter. It is contemplated that the entire converter be shielded by enclosing it in a suitable compartment of metal so as to prevent radiation of energy which might cause interference with telephone lines and radio apparatus. It has been found in practice that a condenser 15 of about 1 m. f. capacity connected between the shield 16 and one of the power leads 4 is desirable and beneficial in preventing radiation of energy which might interfere with nearby radio receiving apparatus.

A fuse 17 is connected in series with the coil 12d between the outer end of the coil 12d and the point where the coil is connected to the common junction of the filament circuit and the positive of the lead wires 4. If desired an incandescent lamp of suitable size may be substituted for either of the resistances 8 and the power which would otherwise be dissipated in the form of heat may be utilized for illuminative purposes and also serve as a pilot light to indicate that the filaments are energized.

The circuit including the condenser 10, oscillators 1 and 2 and the transformer comprises an oscillatory circuit capable of producing a high voltage alternating current of high frequency which may be used to operate suitable apparatus or devices wherein such a current is needed. The invention has been described as being used in connection with a luminous tube comprising an advertising sign but it is to be understood that it may be used for other purposes as well.

It may be found necessary to alter the ratio of coils 12a, 12b, 12c and 12d or in some cases to place an independent winding or coil upon the oscillating transformer in order to successfully operate the auxiliary device, it depending upon what the device constitutes.

One of the important advantages of the present invention is the elimination of the motor generator which is usually required to convert direct current to high frequency alternating current.

The hereinbefore described construction admits of considerable modification without departing from the invention; therefore, it is the wish not to be limited to the precise arrangements shown and described, which are as afore-

said, by way of illustration merely. In other words, the scope of protection contemplated is to be taken solely from the appended claims, interpreted as broadly as is consistent with the prior art.

80

What is claimed as new, is:

1. Apparatus for converting a relatively low voltage commercial power line current into a high voltage alternating current, for operating luminous tubes and analogous high voltage devices, comprising in combination a first coil, one terminal of which is connected to one side of the line and the other terminal of which is connected to one side of the high voltage device constituting the load, a second coil, one terminal of which is connected to the other side of the line and the other terminal of which is connected to the other side of the high voltage device constituting the load, said coils being inductively coupled, and oscillation generating means, comprising at least one thermionic tube, the plate of which is connected into the body of one of said coils, at a point intermediate the described terminals thereof, and the grid of which is connected into the body of the other of said coils, at a point intermediate the described terminals thereof and the cathode of which is connected across the line.

85

2. Apparatus for converting a relatively low voltage commercial power line current into a high voltage alternating current, for operating luminous tubes and analogous high voltage devices, comprising in combination a first coil, one terminal of which is connected to one side of the line and the other terminal of which is connected to one side of the high voltage device constituting the load, a second coil, one terminal of which is connected to the other side of the line and the other terminal of which is connected to the other side of the high voltage device constituting the load, said coils being inductively coupled, and oscillation generating means, comprising a plurality of thermionic tubes, the plates of which are in parallel and are connected into the body of one of said coils, at a point intermediate the described terminals thereof, the grids of which are in parallel and are connected into the body of the other of said coils, at a point intermediate the described terminals thereof, and the cathodes of which are connected across the line.
